UNITED STATES PATENT OFFICE.

AUGUST MICHAELS, OF MILWAUKEE, WISCONSIN.

AUTOMATIC VALVE.

No. 873,324.

Specification of Letters Patent.

Patented Dec. 10, 1907.

Application filed March 4, 1907. Serial No. 360,627.

To all whom it may concern:

Be it known that I, AUGUST MICHAELS, residing in Milwaukee, in the county of Milwaukee and State of Wisconsin, have invented new and useful Improvements in Automatic Valves, of which the following is a description, reference being had to the accompanying drawings, which are a part of this specification.

10 My invention has relation to improvements in automatic valves.

The object of the invention is to provide an improved form of valve for reducing pressures and for governing and controlling 15 pressures, the construction involving a valve extremely sensitive to the slightest variation in pressure, and thereby adapted on the slightest variation to act in a manner to reduce the pressure and to govern and control 20 the same.

With the above primary object, and other incidental objects, in view, the invention consists of the devices and parts, or their equivalents, as hereinafter set forth.

25 In the accompanying drawings, Figure 1 is a vertical, sectional view of the invention; Fig. 2 is a plan view; and Fig. 3 is a vertical, sectional view of a modified form of construction.

30 Referring to Sheet 1 of the drawings, the numeral 4 indicates a casing, the inner chamber thereof being subdivided by a horizontal partition 5 into upper and lower compartments 6 and 7, respectively. The partition 35 is provided with an opening 8, and the bordering edge of this opening is beveled to form a tapered valve seat 9. Leading to the upper compartment 6 is a steam inlet pipe 10, and leading from the lower compartment 7 is 40 a steam outlet pipe 11.

Within the upper compartment is adapted to operate a valve, preferably of the specific form shown in the drawings, i. e., consisting of the lower tapered portion 12 adapted to 45 accurately fit the tapered valve seat 9, and an upwardly extending reduced portion 13. The upper end of this reduced portion is provided with a chamber 14 which is in communication with the upper compartment 6 by means of ports or openings 15. Depending 50 from the lower end of the tapered portion 12 of the valve is a guide 16. The valve is also provided with a vertical opening 17 which extends through the lower end of said 55 valve and upwardly to the chamber 14. Fitting in this opening rigidly and extending

a slight distance above the upper end of the opening and into the chamber 14 is a vertical tube 18. This tube below the valve extends through the lower connecting disk of the 60 guide 16, and its lower end passes through and rigidly fits in an opening 19 formed through a piston 20, which piston is adapted to move up and down in the lower compartment 7 of the casing. Piston 20 is advisably 65 provided with a suitable packing 21. The upper end of tube 18 which extends slightly into the chamber 14 is formed with a tapered valve seat 22 against which is adapted to be seated a tapered valve 23 carried at the lower 70 end of a rod 24. This rod extends through the top of the casing and has pivotally connected to its outer end a lever 25. This lever is fulcrumed on an arm 26, and at a point between the fulcrum and the outer end of the 75 lever, said lever has pivotally connected thereto and depending therefrom a piston rod 27. The lower end of this rod is connected to a piston 28 which is adapted to reciprocate in a cylinder 29. A tube 30 opens 80 through the bottom of the cylinder, and the lower end of this tube is in communication with the steam outlet pipe 11. The outer end of lever 25 carries a suitable weight 31.

The top or cover of casing 4 is preferably 85 removably connected to the upper end of the casing by means of the threaded connection shown, and rising upwardly from the center of the cover is a post 32. The rod 24 passes centrally through this post, and also through 90 a cap 33 screwed on to the upper end of said post. This post can also be made to serve as a convenient support for the fulcrum 26, said fulcrum having a lower extension projecting at right angles and in the form of a plate 34 95 provided with a threaded opening turned on to the threads of the post. The plate is turned down until it rests on the top or cover, and is held in place by means of a lock nut 35.

100 The lower portion of casing 4 has formed therein a vertical passage 36, the upper end of said passage communicating with the steam outlet pipe 11, and the lower end of the passage registering with a port 37 extending through the wall of the casing and 105 communicating with the lower compartment 7 of said casing. Projecting outwardly from the wall of the casing is a boss 38, said boss provided with a passage 39 which is in line with the port 37. A screw cap 40 is preferably turned on to the outer end of the boss, and a needle valve 41 passes through this 110

screw cap and enters the passage 39. The outer end of this needle valve is preferably provided with a hand wheel 42 for convenience in turning it.

5 A steam gage 43 is applied to the steam outlet pipe 11, in order that the steam pressure in said pipe may be readily discernible at any time.

In explanation of the operation of the 10 form of device illustrated on Sheet 1 of the drawings, it will be assumed that the parts are in the position shown in Fig. 1, and the steam is passing through the steam inlet pipe 10 and entering the upper compartment 6, at 15 a certain pressure, say 100 pounds. This steam, it will be evident, is free to pass through opening 8 and enter the space above the piston 20 in the lower compartment 7 and thence out through the steam outlet pipe 20 11. Some of the steam entering compartment 6 also passes through the ports 15 and into the chamber 14, and thence down tube 18 and out of the lower end of said tube into the space of compartment 7 below the piston 25 20, thence through port 37, and up passage 36 and into pipe 11. The needle valve 39 is so adjusted as to restrict the passage 36, and thereby retard to a certain extent the flow of the steam through said passage, so that said 30 steam becomes effective in exerting an upward pressure against the piston 20 tending to hold the valve portion 12 in its raised position, being assisted by the pressure of the steam against the beveled edge of the valve 35 portion 12. Some of the steam of course which flows through pipe 11 passes up pipe 30 and enters the lower end of cylinder 29. If, now, the pressure of the steam flowing through pipe 11 becomes too great, this 40 excess pressure will act against the under side of piston 28, and overcome the resistance of the weight 31, and cause lever 25 to be turned on its pivot in a direction to push downwardly on rod 24. As rod 24 carries at 45 its lower end the valve 23, said valve is necessarily pushed against the valve seat 22, and hence further flow of steam down tube 18 is shut off. The steam in compartment 6, therefore, exerts a pressure on the shoulders 50 formed at the junction of the lower portion 12 of the valve with the upper portion 13 thereof (the counteracting pressure beneath piston 20 being no longer exerted), and consequently the tapered valve portion 12 is 55 forced downwardly to its valve seat 9, and held firmly thereagainst until the pressure of the steam in pipe 11 is reduced to the required amount. When this reduction occurs, the weight 31 overcomes the pressure 60 beneath piston 28, and consequently said piston moves downwardly, and causes the lever 25 to be turned in a direction to raise rod 24, which necessarily unseats valve 23, and consequently once more opens up tube 18 to the 65 flow of steam therethrough. The steam as

it issues out of the lower end of said tube and fills the space beneath piston 20, exerts pressure upwardly on said piston, and this pressure, in conjunction with the pressure exerted on the beveled edge of the tapered portion 12 of the valve, causes said valve to move upwardly, and hence permits the steam to flow through opening 8 and into compartment 7, and out through pipe 11.

Referring to the modified form of construction illustrated in Fig. 3 of Sheet 2 of the drawings, instead of providing the piston 20 in the lower compartment 7 as in the first described form, a piston 44 preferably provided with a suitable packing, is fitted 75 movably in the upper compartment 6. The valve construction of Figs. 1 and 2 is divided, that is to say, the portion of the valve corresponding to the portion 12 of Figs. 1 and 2 construction, and designated in Fig. 3 by 80 the numeral 12', occupies the same relative position as said portion 12 of Figs. 1 and 2, and is provided with a depending guide 16'. The upper portion of the valve, corresponding to the portion 13 of Figs. 1 and 2, and 85 designated in Fig. 3 by the numeral 13', is secured to the top of piston 44, and is provided with a chamber 14' and ports 15', as in Figs. 1 and 2. It will also be noted that in this modified construction a passage 45 is 90 provided in the wall of the upper compartment 7, and this passage places the space below the piston 44 in said compartment 7 in communication with the space above said piston, a port 46 leading from the upper end 100 of passage 45 into said upper space. Projecting out from the wall of the casing is a boss 47 provided with a passage 48 in line with port 46. A needle valve 49 extends through the cap 50 of boss 47 and into 105 passage 45, and is adapted to restrict the flow of steam from passage 45 into the space of the compartment 6 above piston 44. In the operation of this modified construction, if the parts are in a position shown in Fig. 3, 110 the steam passing through the steam inlet pipe 10 enters the space below piston 44, thence passes through opening 8 and into compartment 7, and thence into and through pipe 11. Some of the steam also enters the 115 compartment 6 by way of the passage 45 and port 46, and then passes through ports 15' into chamber 14', thence down tube 18 and into compartment 7, finally flowing through pipe 11. Under normal conditions or pressures, the valve portion 12' is maintained in the position shown in Fig. 3 by pressure of the steam exerted against the under side of the piston 44 and against the beveled edge of valve portion 12'. If, now, the pressure 120 of the steam in pipe 11 becomes too great, this excess pressure will cause the piston 28 to be raised in the same manner as in the other form of construction, and through the described connections, the rod 24 will be 125 130

moved downwardly, and the valve 23 thereby seated. This cuts off further flow of steam down tube 18, and the steam filling the upper space 6 thereby not only acts 5 against the upper side of piston 44, but also against the portion 13' connected to said upper side of piston 44 causing the piston to descend on account of the fact that this down pressure is in excess of the upward 10 pressure of the steam exerted against the under side of the piston 44. The piston 44 and the portion 13' thereabove are rigidly connected to the valve portion 12' by means of the tube 18, the upper end of said tube 15 opening into the chamber 14' of the portion 13'.

While in Fig. 1 I show the valve 12 provided with the upwardly extending chambered portion 13, and also show in Fig. 3 a chambered portion 13' mounted above the piston 44, yet these chambered portions 13 and 13' are not absolutely essential to the invention, as it is obvious that the same could be omitted and successful results obtained. 20 These chambered portions, however, are conveniently used as a means for assisting in guiding the valve stem 24.

While in the foregoing description I have referred to steam as the actuating medium, 30 yet it is obvious that the invention may be operated by any other desired pressure fluid, to equal advantage.

What I claim as my invention is:

1. In valve mechanism, the combination 35 of a casing having two compartments with an opening or passage therebetween, an inlet for the pressure fluid leading to one of the compartments, an outlet for the pressure fluid leading from the other of said compartments, a valve adapted to seat itself against the opening or passage and thereby close the same, and adapted to be moved away from the end of the opening or passage in order to open the same, a piston movably fitted in one of the compartments, and having such area of pressure surface as to maintain the valve open under a certain pressure and against the contrary pressure exerted upon the valve, a tube having one end connected 40 to the piston and adapted for the flow of the pressure fluid through the piston, and its opposite end communicating with an opening through the valve mechanism, a valve for controlling said opposite end of the tube, and mechanism for raising and lowering the tube valve, said mechanism being in communication with the outlet pipe, and adapted to be 45 operated by the fluid passing through the outlet pipe in a manner to cause a movement of the tube valve toward and to said end of the tube and thus shut off the flow of the pressure fluid through the tube, when said fluid exerts a certain pressure in the outlet pipe, whereby the excess pressure thereby 50 created within the casing is exerted in a direction to close the valve controlling the opening between the two compartments, and when the fluid pressure in the outlet pipe falls below a certain point, the said tube valve is adapted to be operated in a direction 55 away from the end of the tube which it controls to again open the tube to the flow of the pressure agent therethrough.
2. In valve mechanism, the combination 60 of a casing having two compartments with an opening or passage therebetween, an inlet for the pressure fluid leading to one of the compartments, an outlet for the pressure fluid leading from the other of said compartments, a valve adapted to be moved away from the end of the opening or passage in order to open the same, a piston movably fitted in one of the compartments, and having such area of pressure surface as to maintain the valve open under a certain pressure and 65 against the contrary pressure exerted upon the valve, a tube having one end connected to the piston and adapted for the flow of the pressure fluid through the piston, and its opposite end communicating with an opening through the valve mechanism, a valve for controlling said opposite end of the tube, and mechanism for raising and lowering the tube valve, said mechanism being in communication with the outlet pipe, and adapted to be 70 operated by the fluid passing through the outlet pipe in a manner to cause a movement of the tube valve toward and to said end of the tube and thus shut off the flow of the pressure fluid through the tube, when said fluid exerts a certain pressure in the outlet pipe, whereby the excess pressure thereby 75 created within the casing is exerted in a direction to close the valve controlling the opening between the two compartments, and when the fluid pressure in the outlet pipe falls below a certain point, the said tube valve is adapted to be operated in a direction 80 away from the end of the tube which it controls to again open the tube to the flow of the pressure agent therethrough.
3. In valve mechanism, the combination 85 of a casing having two compartments with an opening or passage therebetween, an inlet for the pressure fluid leading to one of the compartments, an outlet for the pressure fluid leading from the other of said compartments, a valve adapted to seat itself against the opening or passage and thereby close the same, and adapted to be moved away from the end of the opening or passage in order to open the same, a piston movably fitted in one of the compartments, and having such area of pressure surface as to maintain the valve open under a certain pressure and 90 against the contrary pressure exerted upon the valve, a tube having one end connected to the piston and adapted for the flow of the pressure fluid through the piston, and its opposite end communicating with an opening through the valve mechanism, a valve for controlling said opposite end of the tube, and mechanism for raising and lowering the tube valve, said mechanism being in communication with the outlet pipe, and adapted to be 95 operated by the fluid passing through the outlet pipe in a manner to cause a movement of the tube valve toward and to said end of the tube and thus shut off the flow of the pressure fluid through the tube, when said fluid exerts a certain pressure in the outlet pipe, whereby the excess pressure thereby 100 created within the casing is exerted in a direction to close the valve controlling the opening between the two compartments, and when the fluid pressure in the outlet pipe falls below a certain point, the said tube valve is adapted to be operated in a direction 105 away from the end of the tube which it controls to again open the tube to the flow of the pressure agent therethrough.

against the contrary pressure exerted upon the valve, a tube having one end connected to the piston and adapted for the flow of the pressure fluid through the piston, and its opposite end communicating with an opening through the valve mechanism, a valve adapted for controlling the last referred to end of the tube, a stem extending from said valve, a cylinder having a tube extending therefrom and communicating with the outlet pipe, a piston within said cylinder, and connections between the piston and the valve stem; whereby the tube valve is adapted to be operated by the fluid passing through the outlet pipe in a manner to cause movement of the tube valve toward and to said end of the tube, and thus shut off the flow of the pressure fluid through the tube, when said fluid exerts a certain pressure in the outlet pipe, whereby the excess pressure thereby created within the casing is exerted in a direction to close the valve controlling the opening between the two compartments, and when the fluid pressure in the outlet pipe falls below a certain point, said mechanism between the cylinder piston and the valve stem is adapted to operate the tube valve in a direction away from said end of the tube to again open the tube to the flow of the pressure agent therethrough.

4. In valve mechanism, the combination of a casing having two compartments with an opening or passage therebetween, an inlet for the pressure fluid leading to one of the compartments, an outlet for the pressure fluid leading from the other of said compartments, a valve adapted to seat itself against the opening or passage and thereby close the same, and adapted to be moved away from the end of the opening or passage in order to open the same, a piston movably fitted in one of the compartments, and having such area of pressure surface as to maintain the valve open under a certain pressure as against the contrary pressure exerted upon the valve, a tube having one end connected to the piston and adapted for the flow of the pressure fluid through the piston, and its opposite end communicating with an opening through the valve mechanism, a valve adapted for controlling the last referred to end of the tube, a stem extending from said valve, a cylinder having a tube extending therefrom and communicating with the outlet pipe, a piston within said cylinder, a piston stem extending from said piston, and a lever fulerumed between its ends and connected between its ends to the said piston, and having one end connected to the tube valve stem, and its other end carrying a weight, whereby the tube valve is adapted to be operated by the fluid passing through the outlet pipe in a manner to cause a movement of the tube valve toward and to said end of the tube and thus shut off the flow of pressure fluid

through the tube, when said fluid exerts a certain pressure in the outlet pipe, whereby the excess pressure thereby created within the casing is exerted in a direction to close the valve controlling the opening between the two compartments, and when the fluid pressure in the outlet pipe falls below a certain point, the tube valve is operated in a direction away from said end of the tube to again open the tube to the flow of the pressure agent therethrough.

5. In valve mechanism, the combination of a casing having upper and lower compartments with an opening or passage between the two and also provided in the wall of the lower compartment with a lead passage, an inlet for the pressure fluid leading to the upper of the compartments, an outlet for the pressure fluid leading to the lower of said compartments, and with which outlet the lead passage communicates, a valve located in the upper compartment and adapted to seat itself against the opening or passage and thereby close the same, and adapted to be moved away from the end of the opening or passage in order to open the same, a piston movably fitted in the lower compartment and having such area of pressure surface as to maintain the valve open under a certain pressure as against the contrary pressure exerted upon the valve, a tube having its lower end connected to the piston and adapted for the flow of the pressure fluid through the piston, and its upper end extending into the valve mechanism, a valve for opening and closing the end of the tube which extends into the valve mechanism, and mechanism for raising and lowering the tube valve, said mechanism being in communication with the outlet pipe and adapted to be operated by the fluid passing through the outlet pipe in a manner to close the tube valve and thus shut off the flow of the pressure fluid through the tube, when said fluid exerts a certain pressure in the outlet pipe, whereby the excess pressure thereby created within the casing is exerted in a direction to close the valve controlling the opening between the two compartments, and when the fluid pressure in the outlet pipe falls below a certain point, said tube valve adapted to be operated in a direction to again open the tube to the flow of the pressure agent therethrough.

6. In valve mechanism, the combination of a casing having upper and lower compartments with an opening or passage between the two, and also provided in the wall of the lower compartment with the lead passage, a valve for restricting said lead passage, an inlet for the pressure fluid and leading to the upper of said compartments, an outlet for the pressure fluid leading from the lower of said compartments, and with which outlet the lead passage communicates, a valve located in the upper compartment and adapt-

ed to seat itself against the opening or passage and thereby close the same; and adapted to be moved away from the end of the opening or passage in order to open the same, a 5 piston movably fitted in the lower compartment and having such area of pressure surface as to maintain the valve open under a certain pressure as against the contrary pressure exerted upon the valve, a tube having 10 its lower end connected to the piston, and adapted for the flow of the pressure fluid through the piston, and its upper end extending into the valve mechanism, a valve to open and close the upper end of the tube, 15 and mechanism for raising and lowering the tube valve, said mechanism being in communication with the outlet pipe, and adapted to be operated by the fluid passing through the outlet pipe in a manner to close the tube 20 valve and thus shut off the flow of the pressure fluid through the tube, when said fluid exerts a certain pressure in the outlet pipe, whereby the excess pressure thereby created within the casing is exerted in a direction to 25 close the valve controlling the opening between the two compartments, and when the fluid pressure in the outlet pipe falls below a certain point, said tube valve adapted to be operated in a direction to again open the 30 tube to the flow of the pressure agent therethrough.

7. In valve mechanism, the combination of a casing having two compartments with an opening or passage therebetween, and the top 35 or cover of said casing provided with an upwardly extending threaded post, an inlet for the pressure fluid leading to one of the compartments, an outlet for the pressure fluid leading from the other of said compartments, 40 a valve adapted to seat itself against the opening or passage and thereby close the same, and adapted to be moved away from the end of the opening or passage in order to open the same, a piston movably fitted in one of the

compartments, and having such area of 45 pressure surface as to maintain the valve open under a certain pressure as against the contrary pressure exerted upon the valve, a tube having one end connected to the piston and adapted for the flow of the pressure fluid 50 through the piston, and its opposite end extending into the valve mechanism, a valve adapted for opening and closing one of the ends of the tube, a stem extending from said valve and through the threaded post, a 55 lever connected at one end to the stem and carrying at its opposite end a weight, a fulcrum arm to which the lever is pivoted at a point between the ends of the lever, the said arm having a lower extension provided with 60 a threaded opening which is turned on to the threaded post of the casing, a cylinder having a tube extending therefrom and communicating with the outlet pipe, a piston within the cylinder, a piston rod extending from the piston and pivotally connected to the lever at a point between the ends of said lever, whereby the tube valve is adapted to be operated by the fluid passing through the outlet pipe in a manner to close the tube valve 65 and thus shut off the flow of pressure fluid through the tube, when said fluid exerts a certain pressure in the outlet pipe, whereby the excess pressure thereby created within the casing is exerted in a direction to close 70 the valve controlling the opening between the two compartments, and when the fluid pressure in the outlet pipe falls below a certain point, the tube valve is operated in a direction to again open the tube to the flow of 75 the pressure agent therethrough.

In testimony whereof, I affix my signature, in presence of two witnesses,

AUGUST MICHAELS.
